(57) **CLAIM**

The ornamental design for a smart phone cover with cloth feature, as shown and described.

DESCRIPTION

FIG. 1 is a top, right perspective view of a smart phone cover with cloth feature showing my new design therefor;

FIG. 2 is a bottom, right perspective view thereof;

FIG. 3 is a top plan view thereof;

FIG. 4 is a bottom plan view thereof;

FIG. 5 is a right side view thereof;

FIG. 6 is a left side view thereof;

FIG. 7 is an end view thereof, the opposite end being identical;

FIG. 8 is a top, right perspective view of a second embodiment of a smart phone cover with cloth feature;

FIG. 9 is a bottom, right perspective view thereof;

FIG. 10 is a top plan view thereof;

FIG. 11 is a bottom plan view thereof;

FIG. 12 is a right side view thereof;

FIG. 13 is a left side view thereof; and,

FIG. 14 is an end view thereof, the opposite end being identical.

The broken lines immediately adjacent the shaded surfaces represent boundaries of the claimed design. All other broken lines depict unclaimed environment. The broken lines form no part of the claimed design.
